UNITED STATES PATENT OFFICE

2,580,423

NEGATIVE RESISTANCE PULSE GENERATOR

Robert C. Guthrie, Washington, D. C.

Application May 29, 1943, Serial No. 488,971

8 Claims. (Cl. 250—27)

(Granted under the act of March 3, 1883, as
amended April 30, 1928; 370 O. G. 757)

1

This invention relates to a novel negative resistance device comprising a multiple grid vacuum tube which is designed to operate independently of secondary emission as employed by the "dynatron" and deviates from the negative transconductance action of the "transitron" through the utilization both of retarding electrostatic fields between the tube elements, and degeneration. This invention also relates to a novel means for producing a series of controllable phase and time length energy pulses such as those employed for unblocking a pulse receiver of the radio echo type at the proper time so as to receive only the desired energy reflection.

It is an object of this invention to provide a novel means for obtaining a negative slope in the grid voltage-plate current characteristic of an ordinary multiple grid vacuum tube.

It is another object of this invention to provide a novel means for obtaining and controlling a negative slope in the grid voltage-plate current curve of a multiple grid vacuum tube.

It is another object of this invention to provide a means for producing a series of controllable phase and time length energy pulses.

Other objects and features of the present invention will become apparent upon a careful consideration of the following detailed description when taken together with the accompanying drawings the figures of which are designed for the express purpose of illustration and not as a definition of the limits of the invention. Reference for the latter purpose is to be had to the appended claims.

Fig. 1 is a schematic diagram of a preferred embodiment of the present invention.

Fig. 2 is a graphical representation of a typical grid voltage-plate current curve obtained from the multiple grid vacuum tube 1 contained in Fig. 1.

Fig. 3 is a graphical representation of a typical input voltage to tube 1, and

Fig. 4 is a graphical representation of typical input and output voltage wave forms of tube 2 in Fig. 1.

It is contemplated by the present invention to provide a means for producing a negative slope in the grid voltage-plate current curve of an ordinary multiple grid tube. It is also contemplated by the present invention to provide a means for producing a controllable phase, substantially square output pulse from a linearly varying input voltage.

Reference is had more particularly to Fig. 1 wherein there is shown a preferred embodiment

of my novel negative resistance device comprising the multiple grid tube 1 and associated circuits. The control grid 3 affords a suitable input connection to the tube by way of lead 20 and also a connection to a bias supply by way of resistances 12 and 13 and potentiometer 14 across which a bias voltage is connected. The suppressor grid 7, like most tubes of this type is tied to the cathode 10 which in turn is connected to ground by way of a single resistance 11. Grids 4 and 6 are tied together and connected to a source of positive potential of somewhat lower magnitude than that connected to the plate 9, while the grid 8 may be connected to ground, to a source of negative potential or even to a source of small positive potential say in the order of one or two volts.

A more complete understanding may be had of the present invention upon careful consideration of the following discussion when read in conjunction with Figures 1 and 2. The change in control grid voltage of the tube 1 is shown in Fig. 2 and laid out along the abscissa as taken with respect to ground. Thus as the control grid 3 is driven in a less negative direction, from say cut-off, the plate current will increase in a manner common to the ordinary amplifier, i. e., as the grid voltage is increased the plate current undergoes a corresponding increase since the voltage on the cathode 10 due to the IR drop across resistance 11 will lag behind the rise in grid 3 voltage until maximum plate current is reached. At this point the voltage difference and consequently the electrostatic field between grids 3 and 4 is such that an increase in potential on grid 3 will merely operate to retard the electrons. Thus as grid 3 is driven further positive some of the electrons are collected by the grid 4 while some escape through the grid 4 meshes and are repelled by the low potential grid 8, while others are collected by grid 6 and still others pass through grids 8 and 6 to be collected at the plate 9. Thus grid 4, which I will hereinafter call the anode in view of its function in the tube, now draws considerable current. As the control grid 3 is driven still further positive, more and more of the electrons which escape from the cathode are collected by grids 4 and 6, and are repelled by grid 8, so that less and less are collected by the plate 9. The anode 4 current which flows through the cathode circuit produces an (IR) drop across the resistance 11 to drive the cathode further positive with respect to the grid 8 until this grid acts to finally cut off the plate current flow. It, therefore, becomes apparent that by

driving the control grid 3 through a finite range of potentials a plate current characteristic with respect to grid voltage similar to Fig. 2 can be obtained. It follows that by the proper biasing of grid 3, in phase input and output potentials can be obtained which is the prime requisite of a negative resistance device. It must be understood that this invention must not be limited to the use of a pentagrid tube since a pentode will provide a similar operating characteristic.

In pentode operation the cathode is again connected to ground by a single resistance, the suppressor grid directly to ground, the screen grid to a source of fixed positive potential of somewhat lesser magnitude than the plate potential, and the control grid to a source of bias supply and an input voltage. The primary reason for arbitrarily selecting the potential on grid 3 is that the potential on this grid determines to a certain extent the maximum value of plate current and the control grid voltage at which it will occur, since the more negative this grid is made the smaller number of electrons are allowed to escape to the plate and consequently requires less retarding action between control grid 3 and anode 4 in order to obtain the desired characteristic.

Reference is again had to Fig. 1 which also shows in detail my novel pulse generator comprising tube 1 and 2 connected in cascade. For the purpose of setting forth this invention in better light let it be assumed that a saw-tooth wave according to Fig. 3 is being fed into tube 1. An input voltage of this type can be readily used when the present invention is incorporated with a radio echo pulse receiver of the class described above. The bias on grid 3 is adjusted by potentiometer 14 so that grid 3 is driven through the conducting region, i. e. from below the lower cut-off value to above the upper cut-off value. Thus as the grid is driven through the conducting region of the tube a negative and approximately parabolic pulse similar to A in Fig. 4 is produced in the output circuit of tube 1. A better understanding of the production of this pulse may be obtained from Fig. 3 which shows, clearly, the saw-tooth input voltage swinging through the conducting region of tube 1 as represented by the two parallel lines g and h. The width of this pulse with respect to the saw-tooth wave is exaggerated considerably for purposes of clarity. Obviously potentiometer 14 can be regulated to vary the voltage level about which the input voltage swings thereby shifting the time phase of occurrence of the negative output pulse as shown by the dotted and solid curves in Fig. 3.

The output of tube 1 is coupled to the control electrode of tube 2, which is also connected through resistances 15 and 16 to a source of positive potential, but may be connected to ground if desired. Triode 2 is biased to draw a heavy plate current by way of the self biasing circuit comprising the variable cathode resistance 13 shunted by a large capacitance 19 which operates to maintain the bias constant for rapid variation in input potential. As the leading edge of the parabolic output pulse of tube 1 drives grid 21 in a negative direction there is no immediate reduction in plate current since condenser 19 discharges simultaneously to maintain the voltage difference between cathode 17 and grid 21 constant. After grid 21 is driven negative to point a as shown in curve A of Fig. 4, which exceeds the diminishing positive bias on the cathode 17 a decrease in plate current is occasioned by each increase in negative potential on the grid until

cut-off is reached at point b. The tube will then remain at cut-off over the zero slope of the input voltage as shown in curve A as extending from points b to c until the grid is driven less negative from c to d to cause plate current to flow again and thereby recharge condenser 19 and thus resume normal bias on the tube. The further driving of grid 21 in a less negative direction merely causes rectified grid current to flow and thus results in a further charging of condenser 19 to compensate for the less negative grid voltage. It, therefore, becomes apparent that the effective input voltage to tube 2 is shown in curve B of Fig. 4 which obviously produces an output voltage according to curve C. Thus if resistance 18 is properly regulated the effective time of charge and discharge of condenser 19 can be varied to regulate the spacing between the dotted lines e and f and consequently a relative time length and amplitude adjustment of the output pulse will result.

Although I have shown and described only certain and specific embodiments of the present invention, I am fully aware of the many modifications possible thereof. Therefore, this invention is not to be restricted except insofar as is necessitated by the prior art and the spirit of the appended claims.

The invention described herein may be manufactured and used by or for the Government of the United States of America for governmental purposes without the payment of any royalties thereon or therefor.

I claim:

- 35 1. The combination of, a vacuum tube having at least a plate, a cathode, a screen grid, a control grid and one other plate current control electrode between the screen grid and the plate, means applying fixed operating potentials to said screen and plate electrodes, an unbypassed resistor returning said cathode to ground for causing the cathode potential to follow the signal variations applied to the control grid, signal input means coupled to said control grid for delivering large positive signal voltage variations thereto, and means returning said other plate current control electrode to a point of potential negative of the cathode whereby increases in cathode potentials cause a decrease in plate current.
- 40 2. A means for producing an energy pulse comprising, an electron tube having anode, cathode and grid electrodes, means providing said tube with an inflection point in its transconductance characteristic, said inflection point being bounded on one side with a positive transconductance region and on the other side with a negative transconductance region, an output circuit coupled to the anode of said tube, and signal input means coupled to the grid electrode of said tube for sweeping the operating point of said tube across the inflection point of said transconductance characteristic whereby an impulse is formed in the output circuit of said tube.
- 45 3. A means for producing an energy pulse comprising, an electron tube having anode, cathode, and grid electrodes, means providing said tube with an inflection point in its transconductance characteristic, said inflection point being bounded by a positive transconductance region on one side thereof and a negative transconductance region on the other side thereof, an output circuit coupled to the anode of said tube, means statically biasing the operating point of said tube to one side of the inflection point of said transconductance characteristic, and a sawtooth sig-

nal input means coupled to the grid electrode of said tube to sweep the operating point of said tube across the inflection point of said transconductance characteristic whereby an impulse is formed in the output circuit of said tube.

4. A means for producing an energy pulse comprising, an electron tube having anode, cathode, and grid electrodes, means providing said tube with an inflection point in its transconductance characteristic, said inflection point being bounded by a positive transconductance region on one side thereof and a negative transconductance region on the other side thereof, an output circuit coupled to the anode of said tube, means statically biasing the operating point of said tube to one side of the inflection point of said transconductance characteristic, and a saw-tooth signal input means coupled to the grid electrode of said tube to sweep the operating point of said tube across the inflection point of said transconductance characteristic whereby an impulse is formed in the output circuit of said tube, and means regulating the biasing of said operating point to control the time occurrence of said impulse relative to the initiation of said saw-tooth signal.

5. A means for producing an energy pulse comprising, an electron tube having anode, cathode, and grid electrodes, means providing said tube with an inflection point in its transconductance characteristic, said inflection point being bounded by a positive transconductance region on one side thereof and a negative transconductance region on the other side thereof, an output circuit coupled to the anode of said tube, means coupled to the grid electrode of said tube sweeping the operating point of said tube across the inflection point of said transconductance curve whereby an impulse is formed in the output circuit of said tube, and limiting means coupled to said output circuit operative responsive to the output of said tube for shaping said impulse.

6. A means for producing an energy pulse comprising, an electron tube having anode, cathode, and grid electrodes, means providing said tube with an inflection point in its transconductance characteristic, said inflection point being bounded by a positive transconductance region on one side thereof and a negative transconductance region on the other side thereof, an output circuit coupled to the anode of said tube, means coupled to the grid electrode of said tube operative to sweep the operating point of said

tube across said inflection point of said transconductance characteristic whereby an impulse is formed in the output circuit of said tube, limiting means coupled to said output circuit operative responsive to the output of said tube for shaping said impulse, and means incorporated in said limiting means for selectively controlling the duration and amplitude of the output thereof.

7. The method of generating a voltage pulse 10 in the plate circuit of a grid controlled vacuum tube having an inflection point in its transconductance region, said inflection point being bounded on one side by a positive transconductance region and on the other side by a negative transconductance region, which comprises, biasing said tube for operation on one side of said inflection point, and then rapidly shifting the operational point of said tube from said one side of said inflection point to the other side thereof to thereby produce a momentary pulse of current in the plate circuit of said tube.

8. The method of generating a voltage pulse 15 in the plate circuit of a grid controlled vacuum tube having an inflection point in its transconductance region, said inflection point being bounded on one side by a positive transconductance region and on the other side by a negative transconductance region, which comprises, biasing said tube for operation on one side of said inflection point, rapidly shifting the operational point of said tube from said one side of said inflection point to the other side thereof to thereby produce a momentary pulse of current in the plate circuit of said tube, and then converting 20 said momentary pulse of current into a substantially rectangular voltage pulse.
